Patented Sept. 21, 1915.

UNITED STATES PATENT OFFICE.

HARRY W. LAWRENCE, OF DENVER, COLORADO.

COMBINED REMOVABLE-KEY SINGLE-PIECE SHELL AND AUTOMATICALLY-INTERLOCKING SHELL AND SWITCH-MECHANISM SOCKET

1,154,257.

Specification of Letters Patent. Patented Sept. 21, 1915.

Application filed May 12, 1914. Serial No. 838,092.

To all whom it may concern:

Be it known that I, HARRY W. LAWRENCE, a citizen of the United States of America, residing in the city and county of Denver and State of Colorado, have invented a new and useful Combined Removable-Key Single-Piece Shell and Automatically-Interlocking Shell and Switch-Mechanism Socket, of which the following is a specification.

10 My invention relates to a combined removable key single piece shell and automatically interlocking shell and switch mechanism socket; and the objects of my invention are: first, to provide in an electric light socket, 15 a removable switch key, a one piece shell, and means for removably securing the switch supporting casing to the shell and for removably attaching the key to the switch; second, to provide a simple and integral 20 monolithic structure socket shell and an attachable and detachable switch operating key, and, third, to provide in an electric light socket, a one piece integrally formed shell, to which the switch mechanism automatically locks itself against accidental displacement, and a key that can be attached and the light turned on or off as desired and then be removed from the switch and shell until the operator desires to again turn on 25 or off the light. I attain these objects by the mechanism illustrated in the accompanying drawings, in which:

Figure 1, is a side elevation, showing my improved lamp socket in connection with a lamp of the usual type. Fig. 2, is a vertical sectional view showing the socket and the other coöperating elements constituting my invention. Fig. 3, is a horizontal sectional view of Fig. 1, on the line of the switch-operating shaft. Fig. 4, is a vertical, sectional view of the socket, on a line at right angles to that of the section shown in Fig. 2, the switch mechanism being removed. Fig. 5, is a longitudinal sectional view of 45 the detachable key. Fig. 6, is a perspective view of the switch mechanism, showing the switch operating shaft as constructed in accordance with my invention. Fig. 7, is a transverse, vertical sectional view of the 50 switch mechanism. And Fig. 8, is an end view of the detachable key.

Similar letters of reference refer to similar parts throughout the several views.

Referring to the drawings,—The numeral 1 designates the outside finished and artistically arranged shell of an electric light socket; and 2 designates the inside switch mechanism supporting casing, which is adapted to fit in and be secured to the outside shell 1, so that it will not become accidentally displaced or fall or come out of the shell.

The shell of my improved socket is preferably of the type shown and claimed in my copending application, Ser. No. 838,093, 65 being made of one single integral monolithic piece, without any seams or joints; but it can however be made out of metal, for instance thin brass, the same as most all sockets are made now, by lining the inside of the 70 metal shell with a non-conductive lining, such as wood fiber, which is commonly used, or any other suitable material.

My improved single piece shell should be made of a non-conductive material, and I 75 preferably use porcelain. The upper end of the switch supporting casing 2, is also made of a non-conductive material, while its lower end 3 is made of metal and is connected in any suitable manner to the casing 2.

In all sockets on the market at present, the outside shell which is invariably made of thin metal, is made in two or more pieces, and is so constructed that its parts can be telescoped over the opposite ends of the 85 switch supporting mechanism and its supporting casing, and these divided parts are arranged to meet at or adjacent to the socket and to fit around its shank. This divided construction of the shell is made necessary in 90 the present state of the art, because the switch keys are fastened permanently against either accidental or intentional displacement by persons desiring to manipulate the socket by turning the light on or off by 95 means of the key.

My present invention, however, enables a shell to be made in one integral piece, thus very materially reducing its cost of production, thus furnishing a shell stronger, 100 neater, more artistic in appearance, and one that cannot become accidentally separated around the key, as those now in use sometimes do.

My present invention also provides a 105

switch when an operator desires to turn on the light, and can be removed by the operator and no one can turn off the light unless the key be produced and applied to the switch. Consequently an operator can turn on a light and carry the key with him, and the light cannot be turned off by any one but himself; and having turned the light off, he detaches the key and knows it cannot be again turned on by any one but himself unless he produces the key or informs another where it is, in case he does not carry it with him.

In order that a one piece shell may be made, it is essential that some means be employed to lock the switch supporting mechanism to the interior of the shell. There are a number of ways in which this feature of my invention may be carried out, and my invention contemplates broadly any and all means by which this feature can be accomplished. I, however, illustrate a means which I preferably use for locking the supporting casing of the switch mechanism automatically.

My preferred means for automatically locking the switch mechanism to its outer shell, consists of providing the key operating shaft 4 of the switch mechanism, with a resilient lateral or transverse movement of sufficient resilient reciprocal stroke to allow the operating shaft, to be pressed down toward the outside surface of the switch mechanism against its resilient means far enough to allow the switch mechanism to be inserted in the shell and then to spring outwardly beyond the outside surface of the switch mechanism under an expansive resilient pressure into the key-hole aperture 6, with which all shells are provided, into which the switch operating key is extended.

The outer shell of my improved socket is provided with an aperture that is especially adapted to receive both the switch key and also the outer end of the switch operating shaft, which is positioned on the switch mechanism to resiliently bound or spring into this aperture when the switch mechanism and its supporting mechanism are pushed into their operative position into the outer shell, and in order to provide that the key receiving resilient shaft of the switch can easily be arranged to move directly into the key and operating shaft receiving and locking aperture of the shell. I provide the interior peripheral surface of the shell with a keyway 7, which extends from the outer end of the outer shell to the aperture 6. The outer end of the switch operating shaft fits loosely into this keyway when compressed or pushed into switch casing and entered into the keyway, when it will slide along the keyway as the switch casing is pushed into the shell until it enters the aperture 6, when it will spring into this

aperture and thus lock the switch casing against accidental displacement from the shell.

The switch shaft 4 acts to manipulate the switch mechanism to turn the electric light on or off, as is well understood, and this shaft as illustrated is arranged in the following manner, to move under resilient pressure with a reciprocal stroke movement that does not interfere with the normal and regular turning movement, that operates the switch mechanism to turn on or off the electric light: The inner end of the shaft is rotatably mounted in a bearing aperture formed in the end 9 of an angular yoke-shaped bracket member 10, that is secured to the casing of the switch mechanism, the opposite end of which is provided with an angular end 11 that is provided with a bearing aperture through and beyond which said shaft extends, and in which it is rotatably mounted. This shaft, in addition to rotating freely in its bearings 10 and 11, also has a longitudinal reciprocal movement in them sufficient to allow its free end to move into the key hole of the shell, and thereby lock the free end of this shaft into the shell. This longitudinal reciprocal movement of the shaft is defined in one direction of its reciprocal movement by a pair of laterally projecting lugs 13, that are pressed out of the metal of the opposite sides of the shaft, and which are positioned to bear against the inside surface of the angled end 11 of the yoke shaped bracket, when it is moved to the end of its outward stroke, and the shaft is normally held in this extreme outward position or end of its reciprocal stroke by a spring 14, which may be arranged, together with co-operating means on the shaft, to exert an expansive resilient pressure on the shaft, by any suitable means that will hold it with its lugs 13 against the inside surface of the angled end 11 of the yoke bracket. I preferably, however, arrange the spring and shaft to hold it under expansive resilient pressure in the following manner: A flat blade spring 14 is secured at one end to the bracket 10 and its opposite end 15 is provided with an aperture 17. This end 15 is bent up and is mounted on the shaft, which extends loosely through the aperture 17, and this free end 15 of the spring is arranged to bear with a resilient expansive tension against an abutment mounted on or secured to the shaft; as illustrated, however, I use for this abutment the switch operating block 16, which is provided with an axial aperture 18, and is mounted loosely on the shaft, and on its side facing the end 11 of the yoke shaped bracket, it is provided with an open slot 19, that extends entirely across its central portion. The shaft is provided adjacent to the spring 14 with oppositely projecting lugs 20, that are preferably pressed

out from the metal of its opposite sides, and these lugs fit loosely in the slot of the switch actuating block, which has a slight rotative compensating or relief movement on them, and the shaft, to allow the shaft to be free, and the opposite ends of the switch and its sides which are flat, to bear firmly against the switch actuating spring 21. This spring 21 does not form any part of my present invention, but is illustrated inasmuch as I preferably use the switch block as the abutment block for the resilient expansive spring 14 that holds the shaft at all times when not forcibly pressed in against it, out into the key-hole of the outer shell to lock the switch mechanism to the shell. And while I preferably use this switch block as the abutment for the spring 14, and make it act in the switch to perform these two functions, I could use an additional collar or a shoulder portion on the shaft to act as an abutment for the spring 14 to bear against, and said collar or shoulder would be independent of the switch block but would add additional labor to the cost of producing the socket, which is unnecessary, as the switch block fully answers the purpose. The resilient end of the spring 14 consequently is arranged to bear constantly with a resilient expansive pressure against the switch block, and presses it against the side lugs 20, and consequently forces the side lugs 13 against the inside surface of the angle end 11 of the yoke shaped bracket 10, which holds the shaft always extending into the key-hole of the shell and locks the switch mechanism to the shell against displacement, and the switch casing and its mechanism can only be unlocked from the shell by a skilled mechanic that knows how to press the shaft into the switch and at the same time move it out of the key-hole into the keyway slot 7 while he is holding the pressed shaft below the inner edge of the key-hole. Then he can draw the switch mechanism and its supporting casing out of the outer shell. The outer end of the switch actuating shaft that projects into the key-hole of the shell, is provided with means by which a finger grasping key can be inserted in the key-hole and be instantly attached and locked to it in such a manner as to turn the shaft and operate the switch mechanism to either turn on the light or to turn it off, and then to instantly be removed from the end of the switch shaft. There are a number of ways in which this feature of my invention can be carried out, and my invention contemplates broadly any and all ways and means by which a key can be removably attached to the end of the shaft in such a manner as to enable an operator to turn the shaft to manipulate the switch mechanism to either turn on or turn off the electric light. I preferably, however, carry out this feature of my invention in the

following manner: The extreme terminal end 22 of the shaft, is preferably made into a round short stem portion, at the inner end of which oppositely projecting lugs 23 are formed, on diametrically opposite sides of the shaft, by pressing out the metal from its adjacent sides. These oppositely arranged lugs form side wings and a key 24 is provided, having a socket form of stem 25, which may be secured to the finger grasping piece of the key in any suitable manner, but which as illustrated extends through the finger piece and is secured at the inner end of the finger piece by a pin 25^a, that extends through the stem and is seated in a slot 25^b, formed in the lower end of the finger piece, while the outer end of the stem is threaded and a nut 25^c is inserted in the finger piece and is threaded to it. The lower end of the stem fits loosely in the key-hole of the shell and is provided with an axial bore, that fits over the round stem shaped terminal end of the shaft, and the opposite side of the stem portion of the key is provided with oppositely arranged slots 27, that are large enough to fit loosely over the side lugs at the end of the shaft, and that extend through the stem into its axial aperture, and extend from its end to a point far enough above its end to allow the stem of the key to be pushed on the end of the shaft with its side slots straddling the side lugs 23, which fit loosely but snugly in the slots 27. The key is thus removably locked to the shaft and the shaft can be turned in either direction to turn on or off the light, while the key can be inserted in the key-hole and on the shaft and be removed therefrom at the will of the operator.

The outer shell of my removable key one piece shell socket acts as an insulating as well as an artistic and finished covering for the switch casing and its mechanism, and when made wholly of porcelain or other insulating material, acts as a perfect insulating covering shell. When made, however, of metal, as it can be if desired, it is necessary to use an insulating sleeve that is made to fit the inside surface of the shell closely. This insulating shell is made of wood fiber or any other suitable material, and is used with the divided two or more part socket shells at present in use, and I do not illustrate this insulating sleeve, as it is in common use. But whether my improved shell is made wholly of porcelain or any other insulating material, or of metal such as thin brass, which is mostly used, it is made wholly in one integrally constructed piece, and is provided with an axial aperture, that is arranged to fit loosely over the casing of the switch, and on its outside it is provided around the key-hole with a raised reinforcing boss 29, that makes the shell thick enough to allow the end of the switch shaft to extend far enough into the key-hole to

4

thoroughly and safely lock the switch casing and mechanism to the shell, and at the same time to allow a depth of key-hole above the terminal end of the switch shaft so that 5 there will be no possibility of the end of the shaft coming in contact with anything that would short circuit the switch. This reinforced key-hole also allows a long supporting aperture for the stem of the key, which 10 insures a firm steady journal bearing for the stem of the key to rotate in when inserted in the key-hole and connected to the end of the switch shaft, and in which the key can be left permanently if desired without any 15 danger of its working off from the end of the shaft and falling accidentally out of the key-hole, and from the shell. The upper end of the shell contains an aperture 30, which extends into its axial bore and is 20 adapted to receive the circuit wires which connect to the switch mechanism, as is well understood. The outside surface of the shell may be provided with ornamental beads, moldings, or other members, and such other 25 embellishments as are desired to give it a finished and artistic appearance. The operation of inserting the switch casing in the shell is as follows:

The axial bore of the shell and the outside 30 diameter of the switch casing, are made of such relative sizes that the switch casing will fit snugly but slidably in the axial bore of the shell, and an electrician installing my improved removable key switch, has to enter the end of the casing into the shell until the end of the switch shaft strikes the end of the shell; then he pushes the shaft, which stands about an eighth to three-sixteenths of an inch above the outside surface of the 40 casing, into the switch mechanism and casing until its end will enter the key way 7 in the inner peripheral wall of the shell, and having entered the end of the shaft, he pushes the switch casing into the shell until 45 the switch shaft springs into the key-hole, when the switch casing is securely locked to the shell. The socket is then ready to receive the detached and attachable and removable finger operating key, which, can be 50 applied and left there or can be kept away from the socket until it is turned over to some one who is to control the socket and light.

My invention provides a new type and 55 kind of an electric light socket that is novel in construction and manipulation, to control the turning on or shutting off of the light, and while I have illustrated and described the preferred construction and arrangement of my removable key single piece shell and automatically interlocking shell and switch mechanism socket, I do not wish to be limited to the construction and arrangement shown and particularly described, as many changes might be made

without departing from the spirit of my invention.

Having described my invention, what I claim as new and desire to secure by Letters Patent, is:

1. A lamp-socket, comprising an integral shell having a keyhole, a unitary switch-mechanism adapted to automatically lock itself within said shell when inserted, an operating shaft in alinement with said keyhole 70 and extending thereinto to form part of the locking means, and a quick-detachable key in said keyhole on said shaft.

2. In a socket, an integral monolithic structure shell provided with a switch key 80 receiving key-hole, a switch within said shell having a resiliently mounted actuating shaft extending into said key-hole and arranged to lock said switch to said shell, and a switch key fitting the key-hole of said shell and arranged to be removably locked to said switch shaft.

3. In a socket, the combination of an outer shell member made of one piece of any suitable insulating material, and provided with an axial bore, and a key-hole extending through said shell into said bore, and a key-way extending from the end of said shell along said bore to said key-hole, with a switch mechanism fitting in said shell and provided with a switch controlling shaft having a resilient reciprocal movement, and arranged to project resiliently and slidably into said keyway and into said key-hole thereby to lock said mechanism to said shell, 100 the end of said switch shaft that projects into said key-hole being provided with key members whereby it may be turned, a removable key fitting said key-hole, and means for locking said key to the key members of 105 said switch shaft.

4. In a removable key, one piece shell socket, the combination of a one piece outer shell member provided with a reinforced key-hole, with a switch mechanism arranged 110 to be slidably inserted in said shell and provided with a switch shaft extending beyond the surface of the switch mechanism, said shaft having a reciprocal movement in said switch mechanism of enough stroke to allow 115 it to be moved into said mechanism far enough to allow said mechanism to be inserted in said shell, a spring arranged in said mechanism to hold said shaft normally at the outward end of its resilient movement, 120 said shaft being arranged to spring resiliently into said reinforced key-hole when said mechanism is inserted in said shell, and thereby automatically to lock said mechanism to said shell against accidental displacement, keying members on the outer end of said shaft, and a separate and removable key fitting said reinforced key-hole and provided with means including an axial aperture arranged to allow it to fit over the end 125

of said shaft, and key locking means arranged to lock it to said shaft whereby said key can be applied to said key-hole and shaft and the switch mechanism manipulated to 5 turn on or off the light when said key can be removed from said socket.

5. In lamp socket switch mechanism, the combination of a socket having a key-hole, a switch operating shaft in said socket having 10 an endwise movement, a spring for holding said shaft at the limit of its endwise movement in one direction to normally project into said key-hole, and a detachable key for turning said shaft.

15 6. In lamp socket switch mechanism, the combination of a socket having a key-hole, a support, a switch operating shaft slidably and rotatably mounted therein, a spring on 20 said support for throwing said shaft in one direction to normally project into said key-hole, stops on said shaft for engaging the support to limit the end thrust of the shaft, and a key detachable with respect to said shaft.

25 7. In a device of the character described, the combination with a socket having a key-hole in its wall, and an interior vertical groove extending from the mouth of said socket to said key-hole, of a support, a switch -operating shaft slidably and rotatably mounted in said support, a spring for throwing said shaft in one direction and stops on said shaft which engage the support to limit the thrust of said shaft, said 30 shaft being pressed against the action of said spring to permit its operating end to enter the groove in said socket when inserting the support therein, said spring acting to project the said operating end of the 35 shaft into the key-hole when the said end passes out of said groove, thereby to lock said support to said socket, and a detachable key which is inserted in said key-hole to engage and turn said switch operating 40 shaft.

45 8. In a device of the character described, the combination of a one-piece socket having a key-hole extending through its wall, and an interior guide groove extending 50 from the open end of the socket to said key-hole, a support in said socket, a switch-operating shaft slidably and rotatably mounted in said support, a spring on said support for normally projecting the operating 55 end of said shaft into said key-hole, stops on said shaft for engaging said support to limit the thrust of said shaft, lateral projections on said shaft adjacent to its operating end, and within the socket, and a detachable key which is inserted in said key-hole and over the end of the shaft, having a bifurcated end which engages the 60 said lateral projections, thereby to turn said shaft, the operating end of said shaft lying in said guide groove, when inserting 65

said support, and being thrown to project into the key-hole, by the said spring, when the support is wholly inserted in the socket.

9. The combination of a socket having an interior guide groove terminating in a key-hole extending through the wall of said socket, a support in said socket, a slideable and rotatable switch shaft in said support, a spring on said support for normally throwing said shaft to cause its operating end to project into said key-hole, and a detachable key for the operating end of said shaft, which is inserted in said key-hole, said shaft being depressed to cause its operating end to enter the guide groove in 70 inserting and withdrawing said support.

10. A lamp-socket, comprising a shell having a keyhole, a block in said shell, a U-shaped support secured to said block, a switch in the shell, a transversely slideable switch-operating shaft having its bearings in the legs of said support, a spring for normally maintaining said shaft toward the keyhole so that one of its ends projects 75 into said keyhole, a detachable key for operating said shaft, and means for limiting the transverse movement of the shaft.

11. A lamp-socket, comprising a shell having a keyhole, a block in said shell, a U-shaped support secured to said block, a rotary switch in said shell, a transversely slideable switch-operating shaft having its bearings in the legs of said support, a spring for normally maintaining said shaft toward the keyhole so that one of its ends projects 80 into said keyhole, lugs on said shaft lying normally against the inner side of the leg of said U-shaped support adjacent said keyhole for limiting the outward movement of said shaft, and a detachable 85 key for rotating said shaft.

12. A lamp-socket, comprising a shell having a keyhole and an interior groove extending from the socket opening to said keyhole, a block in said shell, a U-shaped support secured to said block, a switch in the shell, a switch-operating shaft having bearings in the legs of said support, said shaft being transversely slideable to enable 90 said groove to receive one end of the shaft when said block with the support and switch are inserted in the shell, a spring for normally maintaining said shaft toward the keyhole so that said end projects into said keyhole when the parts are assembled, a detachable key for operating said shaft, and means for limiting the transverse movement of the shaft.

13. A lamp-socket, comprising a shell having a keyhole and an interior groove extending from the socket opening to said keyhole, a block in said shell, a U-shaped support secured to said block, a rotary switch in said shell, a switch-operating shaft having bearings in the legs of said 100

support, said shaft being transversely slideable to enable said groove to receive one end of the shaft when said block with the support and switch are inserted in the shell, 5 a spring for normally maintaining said shaft toward the keyhole so that said end projects into said keyhole when the parts are assembled, lugs on said shaft lying normally against the inner side of the leg of 10 said U-shaped support adjacent said keyhole for limiting the outward movement of said shaft, and a detachable key for rotating said shaft.

14. A lamp-socket, comprising an in-

tegral shell having a keyhole and an inferior groove extending from the socket opening to said keyhole, a switch having a laterally movable operating-shaft engaging said groove when the switch is inserted, and a key extending into said keyhole and 20 detachably secured to said shaft when the parts are assembled.

In testimony whereof I affix my signature in presence of two witnesses.

HARRY W. LAWRENCE.
